UNITED STATES PATENT OFFICE.

WALLACE J. HOTCHKISS, OF ALPENA, SOUTH DAKOTA.

FOOD-CONTAINER OR LUNCH-BOX.

1,310,571.

Specification of Letters Patent. Patented July 22, 1919.

Application filed March 8, 1919. Serial No. 281,391.

To all whom it may concern:

Be it known that I, WALLACE J. HOTCHKISS, a citizen of the United States, residing at Alpina, in the county of Jerauld and State of South Dakota, have invented certain new and useful Improvements in Food-Containers or Lunch-Boxes, of which the following is a specification, reference being had to the accompanying drawings.

10 This invention relates to containers, and particularly to lunch boxes or dinner pails, that is receptacles for containing food.

The general object of the invention is to provide a receptacle of this character formed 15 of two sections hinged to each other for movement into or out of abutting relation, each of said sections being provided with a plurality of drawers, shelves, or other removable special receptacles, these special receptacles being held in closed position in the sections when the sections are swung into abutting relation, but being removable from the sections when the sections all swing out of abutting relation.

20 A further object is to provide improved means for holding the sections in their abutted relation and preventing accidental disengagement of the sections but permitting the sections to be disengaged and swung 25 upon each other when desired.

And a further object in this connection is to provide a latching device which is so connected to the bail that when the lunch box or receptacle is carried by the bail, the strain 30 on the bail will hold the sections in their engaged or abutted positions.

Other objects have to do with the details of construction and arrangement of parts, as will appear hereafter.

35 My invention is illustrated in the accompanying drawings, wherein:

Figure 1 is a perspective view of a dinner pail or lunch box constructed in accordance with my invention:

40 Fig. 2 is an elevation of the two sections of a lunch box opened out;

Fig. 3 is a section on the line 3—3 of Fig. 2;

Fig. 4 is a section on the line 4—4 of 45 Fig. 2;

Fig. 5 is a perspective view of a cup designed to be used with my lunch box.

Referring to these drawings, it will be seen that my container is formed in two sections A and B. Each of these sections may have any desired form and each of these

sections is preferably made of thin sheet metal. These sections are open at their adjacent ends but otherwise closed and one section is hinged to the other by hinges 10, 60 certain of the leaves of the hinge being attached to the section A, while certain other leaves are attached to the section B. These two sets of sections are connected by a vertically extending pintle 11. It will thus be 65 seen that these sections may swing with relation to each other from an abutted position to a more or less parallel position. The upper end of the pintle 11 is formed with an eye 12 and a bail 13 is, at one end, formed 70 with a hook to engage said eye. At the opposite side of the device, the section B is provided with an outwardly extending tongue 14 which is vertically grooved or recessed, as at 15, and when the section B is closed 75 against the section A, this tongue engages beneath a keeper 16. This tongue fits the keeper snugly so as to assist the hinges in supporting the sections in the same vertical plane and take off the strain on the hinges. 80

Pivotal mounted upon the lower end of the section A adjacent its inner, open end, is a vertical rod 17 formed with an eye 18 at its upper end for engagement with the hook of the handle or bail 13. This locking rod 85 17 at its lower end is disposed in a socket member 19 which, at its lower end, is formed with an opening 20 through which the lower, angularly bent end of the rod 17 passes so as to form a pivotal support for 90 this rod. This socket has a straight side wall 21 and an inclined side wall 22 and is, of course, open at its upper end so that the rod 17 may be oscillated within the socket into or out of its locking position. When 95 the section B is abutted against the section A and the tongue 14 is inserted within the keeper 16, this locking rod 17 will engage in the vertical groove 15 of the tongue, which tongue is somewhat resilient and thus 100 the two sections will be locked in abutting relation. Furthermore, when the bail 13 is connected to the eyes 12 and 18 and the lunch box is lifted, it will be obvious that the rod 17 will be held from any movement 105 which would tend to accidentally detach the rod from the groove 15 of the tongue.

Each of the sections A and B may be divided into compartments, but preferably these compartments carry a plurality of 110 drawer-like receptacles or shelves. For instance, I have illustrated the section A as be-

ing divided longitudinally by a horizontal partition 23 and as carrying an upper and a lower receptacle 24 and 25 respectively, these receptacles being of any suitable character and fitting the section snugly. These drawer-like receptacles may have a side wall extending entirely around the margin of the bottom of the receptacle or partially around this bottom, depending upon the character 10 of the food to be carried, and each of these food-carrying receptacles 24 and 25 is formed with a handle 26 projecting very slightly from the front of the receptacle whereby the receptacle may be withdrawn 15 from the section.

I have illustrated the section B as being divided into three compartments. One of these compartments extends the full height of the section and carries in it a relatively 20 large drawer-like receptacle 27 which may be divided into a number of compartments if desired, and which may be used for carrying liquids. Of course, it is obvious that this particular receptacle has a cover 27^a and 25 fits the top of the section closely so as to prevent any slopping out of the liquid. On the other side of the vertical partition 28, which divides the section B, there is one or more horizontal partitions 29, and I have 30 shown upper and lower drawer-like receptacles 30 and 31 respectively disposed in this side of the section. These receptacles may also be provided with an exterior, upstanding rim and I have illustrated one of these 35 drawer-like receptacles 24 as being provided with the upstanding, medially disposed wall 32.

I do not wish to be limited at all as to the number of these receptacles which may 40 be disposed in any section, their arrangement, or the details of their construction. A cup 33, which may be of sheet metal, may be carried in one of the receptacles or shelves, and I have illustrated this cup as triangular in 45 form so that it may be laid flat down upon the shelf and accommodate itself to the angles of the receptacle.

Preferably, though not necessarily, the top of the two sections A and B will be of 50 an ornamental character. Thus, it may be longitudinally corrugated or may be formed with ornamental bosses or protuberances, or be stamped out in ornamental form. It is only necessary that the two sections shall fit 55 closely against each other so that the heat or aroma from the food shall not escape.

It will be understood that I do not wish to be limited to the particular configuration, form, or contour of this structure, as it may 60 be varied in many ways and yet remain the principle of my invention.

I claim:—

1. A lunch box of the character described comprising two sections hinged to each other 65 at one side, the sections being open at their

adjacent ends, drawer-like receptacles disposed within each section and held within their respective sections by abutting against each other when the sections are closed, and a latch member carried upon the free side 70 of one of the sections, a keeper on the other section with which the latch member engages, and a latch device on the last named section engaging with the latch member on the first named section. 75

2. A lunch box of the character described comprising two sections hinged to each other at one side, the sections being open at their adjacent ends, drawer-like receptacles disposed within each section and held within 80 their respective sections by abutting against each other when the sections are closed, a resilient tongue carried upon the free side of one of the sections, a keeper carried upon the free side of the other section and into 85 which said tongue is insertible when the sections are closed, the tongue being vertically recessed, and a locking rod engageable with said recess or disengageable therefrom.

3. A lunch box of the character described comprising two sections hinged to each other at one side, the sections being open at their adjacent ends, drawer-like receptacles disposed within each section and held within 90 their respective sections by abutting against each other when the sections are closed, a resilient tongue carried upon the free side of one of the sections, a keeper carried upon the free side of the other section and into 95 which said tongue is insertible when the sections are closed, the tongue being vertically recessed, and a locking rod engageable with said recess or disengageable therefrom, said locking rod having means for engagement with a bail. 100

4. A lunch box of the character described comprising two sections hinged to each other at one side, the sections being open at their adjacent ends, drawer-like receptacles disposed within each section and held within 110 their respective sections by abutting against each other when the sections are closed, a resilient tongue mounted upon the free side of one of the sections, a keeper mounted upon the free side of the other section into 115 which said tongue is insertible when the sections are abutted, said tongue being longitudinally grooved, a vertically disposed socket carried upon the free side of the last named section and having a lateral opening 120 at its lower end, and a locking rod inserted vertically downward through the socket and angularly bent at its lower end to pass through said perforation to thereby form a fulcrum for the rod, said rod being engageable with the groove in the tongue to lock the sections to each other. 125

5. A lunch box of the character described formed of two sections adapted to be shifted into or out of abutting relation, each of said 130

sections having slidable receptacles mounted therein, hinged leaves attached to the respective sections on one side thereof, a pintle engaging through the hinged leaves 5 and formed with an eye at its upper end, a resilient tongue mounted on the side wall of one of the sections, a keeper mounted upon the side wall of the other section into which said tongue is insertible when the sections 10 are abutted, a locking rod pivotally connected to the last named section for movement in a plane parallel to the side wall of the section and adapted to engage in said groove, the rod being formed with an eye at its upper 15 end, and a bail adapted to detachably engage the eye on the pintle and on said locking rod.

6. A container of the character described comprising two sections, each open at one 20 end, the open end of the sections being adapted to be abutted against each other and carrying a plurality of drawer-like receptacles shiftable into or out of the sections and held in closed position by the 25 abutting of the sections, means for detach-

ably engaging the sections with each other in abutted relation and including hinge members attached to one side of the section, and locking means engaging the other side of the section. 30

7. A container of the character described comprising two open ended sections hinged to each other so that the open ends of the sections may be disposed in abutting relation, means for detachably locking said sections in abutting relation and including a bail, each of said sections being divided into compartments by vertical and horizontal partitions, and a plurality of slidable drawer-like food receptacles disposed in 35 said compartments and having their outer ends formed to fit the walls of said compartments closely, said receptacles having side walls.

In testimony whereof I hereunto affix my 40 signature in the presence of two witnesses.

WALLACE J. HOTCHKISS.
